T. A. PATTERSON.
CHLORIN CELL.
APPLICATION FILED FEB. 17, 1920.

Patented May 25, 1920.

FIG. 1.

FIG. 2.

UNITED STATES PATENT OFFICE.

THOMAS A. PATTERSON, OF NIAGARA FALLS, NEW YORK, ASSIGNOR TO NIAGARA
ALKALI COMPANY, OF NIAGARA FALLS, NEW YORK, A CORPORATION OF NEW
YORK.

CHLORIN-CELL.

1,341,516.

Specification of Letters Patent. Patented May 25, 1920.

Application filed February 17, 1920. Serial No. 359,476.

To all whom it may concern:

Be it known that I, THOMAS ARTHUR PATTERSON, a citizen of the United States, residing at Niagara Falls, N. Y., in the county 5 of Niagara and State of New York, have invented certain new and useful Improvements in Chlorin-Cells, of which the following is a specification.

This invention relates to chlorin cells; 10 and it comprises an electrolytic cell adapted to deliver pure chlorin while working under suction; such cell having a cathode, a diaphragm and one or more anodes with leads therefor and a top or cover through which 15 the anode leads extend, the top or cover being shaped or otherwise provided to hold a bath of sealing liquid around the anode leads, and the anode leads as well as the joints of the top with the cell being sealed 20 by means of luting material; an off-take for chlorin advantageously being similarly luted through the top and similarly sealed by the bath of sealing liquid, all as more fully hereinafter set forth and as claimed.

25 In the manufacture of chlorin and caustic soda (or potash) by electrolysis, it is customary to use some type of diaphragm cell having a closed anode chamber run under slight suction to preclude any possibility of 30 escape of chlorin into the atmosphere of the cell room. The anode chamber is carefully sealed to make it as near gas tight as possible, all joints being luted with a soft plastic material known as chlorin putty. These 35 precautions are taken to prevent, as far as may be, entrance of air to contaminate the chlorin. Nevertheless, with the most careful sealing and luting it is practically impossible to prevent, or even detect, slight 40 leaks in the large cell units used in practice; and therefore the chlorin delivered almost invariably contains some air. Sometimes the amount of air present is large. Even a very small leak in one unit of an 45 assemblage of cells may admit enough air to ruin down the purity of the chlorin from the assemblage a per cent. or so. For many purposes the presence of a little air in the chlorin, while never desirable, may not be 50 very detrimental; but for other purposes, and notably in producing chlorin for liquefaction, the presence of air is highly objectionable. In the presence of air, compression and liquefaction are rendered much 55 more difficult and expensive.

In the present invention I employ a closed type of cell wherein operation may be under suction in the usual manner while producing chlorin free of air. To this end, I use a cell having a cathode and a diaphragm 60 of any usual type. At the top I provide the cell with a cover luted in position. The customary luting means, what is known as "chlorin putty," may be used. Passing through the cover are the anode leads or 65 conductors; these leads being luted in suitable orifices in the usual way. The chlorin offtake may also pass through this cover and be luted in. However carefully these luted joints may be made there is always the possibility of the development of a leak; and frequently the leakage is difficult to discover. It must be remembered that these cells are customarily run rather hot and the luted joints are exposed to the action of 70 steam, chlorin, expansion and contraction, etc. Leaks are bound to develop however carefully the joints may be luted.

In the present invention I obviate the effects of, and render easily detectable, any 75 leaks which may occur by the simple expedient of prolonging the side walls of the cell above the luted top so as to form a shallow open basin, or dished top, the cover or top of the cell carrying the luted joints 80 forming the bottom of the basin. This basin I then fill with water or with brine or other fluid sealing means. Under these conditions, air cannot reach the luted joints 85 and any leakage that there may be is of 90 brine or water. Should a leak develop, it is at once visible by the movement of the liquid. The luted joints of the cover or top, and of the anode leads, are of course 95 readily accessible through the shallow layer 100 of brine or water, and can be readily made tight whenever a leak develops. In other words, the liquid above the cell top acts not only as an additional sealing means to the luting, but also as an indication when leakage occurs at any point.

In the accompanying illustration I have shown one form of cell embodying my invention.

In the drawings, Figure 1 is a top plan 105 view and

Fig. 2 is a vertical section along line 2-2 of Fig. 1.

In this illustration, element 1 represents the side walls of a cell, shown as made of 110

concrete or the like. The cell is shown interiorly lined with tiles in a customary way. At its base the cell is provided with cathode 3 and diaphragm 4; these being of any usual 5 construction. As shown, the cathode is of wire netting or perforated metal. The diaphragm may be made of any of the usual materials. Both are supported by angle irons 5 extending upward from steel casing 10. The space between the casing and the cathode forms a cathode chamber 7, receiving caustic soda solution and hydrogen. It is provided with the usual gas and liquid outlets (not shown). These elements (cathode 15 (angle irons and the bottom casing) may be all electrolytically connected. Within the cell is the usual body of brine, submerged within which are graphite or other anodes 9, carried by current leads 10 extending through the top or cover. The side walls and tiles are recessed at 11 to accommodate this cover 12, which may be made of any suitable material. The joint between the cover and the recess is sealed with luting 20 material 13. The joints at the points where the anode leads pass through the cover are luted, as shown at 14 in the same way. Above the recess, as shown, the side walls have an extension 15, forming with the 25 cover a shallow basin wherein is a body of liquid 16 which may be water or may be brine of the same character as that under electrolysis in the cell. The chlorin offtake 17 leading to the usual chlorin main or 30 manifold (not shown) may be luted through the cover at 18. The sealing liquid which forms a shallow pool, covers all these luted joints. From the construction of the cell no short circuiting can occur because of the 35 presence of this liquid. The liquid may be drawn off through valved pipe 19.

In use the cell is run in the usual way under suction removing chlorin through the chlorin offtake 17. The luted joints 13, 14 45 and 18 provide protection against inward leakage of air in the usual way. Should a leak develop no harm results, since there is merely an inward passage or leakage of liquid while at the same time the occurrence 50 of such a leak is at once shown by the motion of the liquid toward it, calling the attention of the attendant to it and allowing him to repair it at once.

By the use of the simple expedient shown, 55 it is easily possible to produce chlorin of 100 per cent. purity without in any way changing the operation of the cell.

The invention has been described as applied to a horizontal chlorin producing cell, 60 but it is of course applicable to vertical cells and for the manufacture of bromin or any other gas or vapor. It is particularly ad-

vantageous in use on cells producing poisonous or deleterious gases or vapors.

What I claim is:—

65

1. A closed electrolytic cell having a gas space with all joints thereof liquid sealed.

2. An electrolytic cell having a cathode and diaphragm, an anode in juxtaposition to the cathode, and a top provided with 70 means for containing a sealing liquid, anode connections leading through said top, and a sealing liquid in said top surrounding said anode connections.

3. A chlorin cell having a cathode and 75 diaphragm, side walls, a cover luted to said side walls, luted anode connections extending through said cover, a luted chlorin offtake extending through said cover and a liquid bath covering the luted joints. 80

4. An electrolytic cell comprising a closed container, for the liquid to be electrolyzed, a cathode therein, an anode supported in proximity with the cathode and having leads 85 extending through the top of the container, and a sealing bath of liquid covering the top of the container and covering the anode lead.

5. An electrolytic cell comprising a closed container for the liquid to be electrolyzed, 90 and having a dished top, a cathode in the container and one or more anodes in the container having leads extending through the dished top, and a bath of sealing medium on the dished top surrounding the anode. 95

6. An electrolytic cell having walls provided with a seat for a top, a top arranged to be seated in such seat, extensions for the walls extending above the said top when the top is seated in position, whereby there 100 is formed a dished receptacle, and a sealing means in the dished receptacle.

7. An electrolytic cell comprising a closed container for liquid to be electrolyzed, a cathode therein, an anode supported in 105 proximity with the cathode and having a lead extending through the top of the container, luting material sealing the said lead in the top of the container, a chlorin offtake passing through the top of the container, 110 luting material sealing the said offtake in the said top, and a sealing bath of liquid covering the top of the container, the anode lead and the said offtake.

8. An electrolytic cell having contained 115 anodes and cathodes and leads for the cathode extending outside the container through the top thereof an offtake extending through the top, and a bath of sealing means located on said top and surrounding said anode 120 leads and said offtake.

In testimony whereof I affix my signature hereto.

T. A. PATTERSON.
